UNITED STATES PATENT OFFICE.

EDWARD THIMGREN, OF POPOTLA, MEXICO.

COMBINED CANE AND TELESCOPE.

Application filed November 14, 1922. Serial No. 600,887.

To all whom it may concern:

Be it known that I, EDWARD THIMGREN, a subject of the King of Sweden, residing at Popotla, Distrito Federal, Mexico, have invented certain new and useful Improvements in Combined Canes and Telescopes, of which the following is a specification.

This invention relates to certain new and useful improvements in combined canes and telescopes wherein the telescope is supported by the handle of the cane in either a housed position within the head or stock of the cane, or removed therefrom to its operative position and supported by the cane.

The primary object of the invention resides in the provision of a combination cane and telescope wherein the head or stock of the cane is provided with a relatively long socket for normally housing a telescope, the latter being removable from the socket and supported on side bars that are slidably associated with the cane head when in its operative position with the side bars adjustably secured at various elevations relative to the cane.

The invention further provides in a combined cane and telescope of the type above set forth, the provision of a cap for the socketed end of the cane that incloses the telescope with a compass carried by the cap.

With the above general objects in view and others that will appear as the nature of the invention is better understood, the same consists of the novel form, combination and arrangement of parts hereinafter more fully described, shown in the accompanying drawing and claimed.

In the drawing, wherein like reference characters designate corresponding parts throughout the several views,

Figure 1 is a longitudinal sectional view of the upper or handle end of a cane showing the socket therein for housing the telescope with the latter supported in its operative position above the cane handle.

Figure 2 is a longitudinal sectional view taken on line II-II of Fig. 1 showing the sliding supporting bars for the telescope guided in grooves formed in the head of the cane with adjusting screws for holding the same in set positions.

Figure 3 is a longitudinal sectional view of the upper end of the cane showing the telescope housed therein and the cover cap closing the outer end of the handle socket with the compass carried by the cap, and

Figure 4 is a cross-sectional view taken on line IV-IV of Fig. 3 showing the configuration of the side grooves in which the supporting bars for the telescope are slidably mounted.

Referring more in detail to the accompanying drawing, there is illustrated a combined cane and telescope, the cane being constructed of any suitable material, such as wood or metal and embodying a stick portion 1 having the upper end or head 2 thereof provided with a relatively deep socket opening at the outer or upper end of the cane head. The side walls of the socketed head 2 are provided with diametrically opposite longitudinally extending grooves 3 having the inner walls thereof longitudinally slotted as at 3^a establishing communication between the socket of the head and the grooves 3 as clearly shown in Figs. 1 and 4.

An elongated rod 4 of cross-sectional configuration similar to the groove 3, as shown in Fig. 4 is slidably mounted in each groove 3 and pivotally support at their upper ends upon pivot pins 5, an extensible telescope 6, a spacing washer 7 being positioned between each rod 4 and adjacent side of the telescope as shown in Figs. 3 and 4. To hold the telescope in its extended operative position as illustrated in Figs. 1 and 2, the opposite side walls of the head 2 adjacent the grooves 3 carry set screws 8 that are threaded through said side walls and adapted for engagement with the outer faces of the rods 4 to hold the supports for the telescope in a rigid position as shown in Fig. 2.

In housing the telescope within the socketed head 2, the extensible sections of the telescope are collapsed, the telescope then being moved upon its pivotal connection 5 with the outer ends of the rods 4 to longitudinally aline the same with the socket in the cane head. The set screws 8 are then released from engagement with the rods 4, at which time the rods and telescope are slidably received within the sockets of the cane head as shown in Fig. 3. The set screws 8 are then tightened, showing a rigid support for the telescope within the socketed head of the cane.

A closure cap 9 covers the open outer end of the socketed head 2, internal threads formed upon the inner end thereof engaging the threads 2^a upon the outer end of the socketed head. As shown in Fig. 3, the outer

end of the cap 9 carries a removable threaded end 10 that covers a compass 11 carried by a supporting plate 12 within the outer end of the cap 9.

5 It will therefore be seen that a novel type of combination cane and telescope is provided, the telescope being rigidly supported within a socketed head carried by the cane to be projected therefrom and rigidly supported in an operative position, the side rods 4 providing a convenient pivotal support for the telescope, permitting the cane to rest upon the ground or other support while the telescope is in use.

10 15 While there is herein shown and described the preferred embodiment of the present invention, it is nevertheless to be understood that minor changes may be made therein without departing from the spirit and scope 20 thereof as claimed.

What is claimed as new is:—

1. In a combined cane and telescope, a cane having a socketed head, side rods longitudinally slidable in opposite side walls of 25 the socketed head, and a telescope pivotally carried by the outer ends of said rods adapted to be housed within the socket of the head and to be projected therefrom and supported by the rods when in use.

30 2. In a combined cane and telescope, a cane having a socketed head, side rods longitudinally slidable in opposite side walls of the socketed head, a telescope pivotally carried by the outer ends of said rods

adapted to be housed within the socket of 35 the head and to be projected therefrom and supported by the rods when in use, and means engaging the rods for holding the same in adjusted position.

3. In a combined cane and telescope, a cane having a socketed head, side rods longitudinally slidable in opposite side walls of 40 the socketed head, a telescope pivotally carried by the outer ends of said rods adapted to be housed within the socket of 45 the head and to be projected therefrom and supported by the rods when in use, and set screws carried by the side walls of the socketed head engaging the side rods for holding the same in adjusted positions. 50

4. In a combined cane and telescope, a cane having a socketed head with longitudinal grooves diametrically disposed in the side walls of the socketed head, a rod slidably mounted in each groove, an extensible telescope pivotally supported at the outer ends of the rods, means for holding the rods in adjusted position, and a closure cap threaded on the outer end of the socketed head with the telescope confined within the 60 head socket.

In testimony whereof I hereunto affix my signature in presence of two witnesses.

EDWARD THIMGREN.
